CLAIM

The ornamental design for a multi-barbed anchor, as shown and described.

DESCRIPTION

FIG. 1 is a perspective view of a multi-barbed anchor, in accordance to the present invention;

FIG. 2 is a front elevation view of the multi-barbed anchor shown in FIG. 1;

FIG. 3 is a rear elevation view of the multi-barbed anchor shown in FIG. 1;

FIG. 4 is a bottom view of the multi-barbed anchor shown in FIG. 1;

FIG. 5 is a top plan view of the multi-barbed anchor shown in FIG. 1;

FIG. 6 is a left side view of the multi-barbed anchor shown in FIG. 1; and,

FIG. 7 is a right side view of the multi-barbed anchor shown in FIG. 1.

The broken lines in the drawings illustrate portions of the multi-barbed anchor and form no part of the claimed design.

1 Claim, 3 Drawing Sheets
